[57] CLAIM

The ornamental design for human figure game die, as shown.

DESCRIPTION

FIG. 1 is a front elevational view of human figure game die showing my new design;

FIG. 2 is a top plan view thereof;

FIG. 3 is a bottom plan view thereof;

FIG. 4 is an rear elevational view thereof;

FIG. 5 is a side elevational view thereof;

FIG. 6 is a side elevational view opposite the side elevational view of FIG. 5;

FIG. 7 is a front elevational view of a modified form of a human figure game die described in FIG. 1;

FIG. 8 is a top plan view thereof;

FIG. 9 is a bottom plan view thereof;

FIG. 10 is an rear elevational view thereof;

FIG. 11 is a side elevational view thereof;

FIG. 12 is a side elevational view opposite to the side elevational view of FIG. 11;

FIG. 13 is a front elevational view of a modified form of a human figure game die described in FIG. 1;

FIG. 14 is a top plan view thereof;

FIG. 15 is a bottom plan view thereof;

FIG. 16 is an rear elevational view thereof;

FIG. 17 is a side elevational view thereof;

FIG. 18 is a side elevational view opposite to the side elevational view of FIG. 17;

FIG. 19 is a front elevational view of a modified form of a human figure game die described in FIG. 1;

FIG. 20 is a top plan view thereof;

FIG. 21 is a bottom plan view thereof;

FIG. 22 is an rear elevational view thereof;

FIG. 23 is a side elevational view thereof;

FIG. 24 is a side elevational view opposite to the side elevational view of FIG. 23.
